B. R. JOLLY,
FOUNTAIN PEN,
APPLICATION FILED NOV. 17, 1916.

1,299,836.

Patented Apr. 8, 1919.

UNITED STATES PATENT OFFICE.

BENJAMIN R. JOLLY, OF RALEIGH, NORTH CAROLINA.

FOUNTAIN-PEN.

1,299,836.

Specification of Letters Patent.

Patented Apr. 8, 1919.

Application filed November 17, 1916. Serial No. 131,955.

To all whom it may concern:

Be it known that I, BENJAMIN R. JOLLY, a citizen of the United States of America, residing at Raleigh, in the county of Wake 5 and State of North Carolina, have invented certain new and useful Improvements in Fountain-Pens, of which the following is a specification, reference being had therein to the accompanying drawing.

0 My invention relates to fountain pens and has for its object the production of a pen of this type which shall be free from certain objections heretofore existing and shall have certain advantages which shall be herein- 15 after pointed out.

As well known, a fountain pen, like a thermometer, is sensitive to changes in temperature, and unless the pen barrel is kept full of ink which is not practical, the ex- 20 pansion of the air in the pen due to any rise in the temperature will force some of the ink out of the pen, producing what is commonly called flooding or leaking. I provide against this condition by constructing 25 a small supplemental reservoir in the pen feed, and connected passages and channels beneath the pen so that a certain amount of ink can be received and retained without overflowing, and at the same time the pen 30 will be ready to write, as this ink will not flow back into the barrel. In addition to this special construction, an incident in the general construction of my pen is to place it under better control of the user so he can 35 readily detect the fact that it is flowing too freely and be enabled to remove the surplus ink from the pen.

Another disadvantage heretofore encountered has been a lack of perfect alinement 40 of the pen with the feed parts and the barrel, due to accident, wear, or imperfect adjustment. As ordinarily constructed, if the pen should spring away at the point or nib, the feed would cease until readjustment is 45 made. Corollary to the alinement proposition, is that of keeping the pen from contact or near approach with or to any projection on the holder or barrel, to which the ink could adhere and be drawn away from 50 the point of the pen by capillary attraction. I meet both these requirements and obviate the objection on the score of alinement, by fastening the middle of the pen to the feed, instead of the reed or stem portion. This 55 enables me also to attain an additional advantage by forming the pen with two points

or nibs, one at each end. Being secured at an intermediate or middle point the pen can be reversed by slight manipulation of the fastening means, and moreover one end is 60 balanced against the other in its pressure against the feed parts, so that perfect contact at all times and perfect alinement are assured. The two points may be the same or different. 65

An additional feature of invention consists of a combination filling device and clip, which without alteration is used to fill the pen, whether the latter is provided or not with a rubber sack, by simple manipulation. 70 When not in use as a filler, the device is carried on the side of the cap and acts as an ordinary clip to hold the pen in the pocket.

My invention is illustrated in the accompanying drawings in which— 75

Figure 1 is a longitudinal sectional view of a pen complete, with cap and filler.

Fig. 2 is a plan view of the cap of Fig. 1 to show the combined clip and filler.

Fig. 3 is a plan view of a cap and clip of 80 modified form.

Fig. 4 is a side view of the clip rod removed.

Fig. 5 is a transverse section on the line 5—5 of Fig. 1. 85

Referring to Figs. 1 and 2, 1 is the barrel of the pen, 2 is the feed plug, which is shoudered and may be threaded at 3 to fit the barrel. 4 is an auxiliary reservoir formed in the feed plug, 5 is an opening from said 90 reservoir through the upper part of the plug, and 6 is a depression in the upper face of the plug, which underlies the pen 7 and is kept filled with ink from the small reservoir 4 by the force of gravity and capillary at- 95 traction. The pen 7 is centrally pivoted at 8 to the plug 2, and by reason of its curvature as shown in Fig. 7, which fits the curvature of the plug 2, it is held in perfect alinement at all times. In the middle of the res- 100ervoir 4 I provide a leader or feed tube 9, containing a central passage which communicates with the small tubular passage 10 through the main body of the plug 2. The flow of ink from the barrel is therefore 105 through the plug and through the tube 9 to its end 11, thence into the reservoir or directly out through the opening 5 to the pen.

The pen 7 is double ended, that is to say it is made with two points, each finished in 110 the usual manner, and tipped with iridium if the pen be of gold as it usually is. Apart

from the mechanical advantages gained by this construction, there is a very great convenience to the user in having two pen points available. One of these may be fine and the 5 other coarse, or one may be a "falcon" point and the other a stub. I believe I am the first to thus provide a fountain pen with interchangeable points, forming a part of the pen itself and not requiring the removal or 10 replacement of the pen. I shall therefore claim the same as part of my invention. Its practical value will be understood when it is considered that many persons, especially traveling men and bookkeepers are compelled to carry at least two pens, since it is 15 impossible properly to make book entries of accounts with a pen adapted for correspondence, or vice versa.

In Fig. 1 the barrel is shown provided 20 with a rubber sack or ink holder 12. This may be dispensed with, without altering the invention.

18 is the cap, which fits over one end of the barrel as shown in Figs. 1 and 2. A 25 double band 14 with a bridge portion 15 is secured around the cap, and carries on one side a spring clip 16, and is provided with ears 17 on opposite sides of one of the bands, and a bail 18 with a central collar 19, in 30 which slides the clip rod 20, which is ordinarily held fast in the spring clip 16, and requires considerable force to be disengaged therefrom. The normal position of the clip rod 20 is shown in Figs. 1 and 2. When it 35 is desired to use the rod as a filler, however, outward pressure is exerted on the end 20^a until it springs free of the clip 16 and turns the bail 18 in the ears 17 until the parts occupy the position shown in dotted lines in 40 Fig. 2. The rod can be slid through the collar 19 and into an opening 21 formed in the end of the cap, to engage the plunger 22, made of leather, rubber, or other suitable material, which is fitted to work in the bore 45 of the cap, like the piston or plunger of a pump.

For the purpose of permitting ready filling, the barrel 1 has an air hole 23 in its upper end normally closed by the screw 50 plug 24.

The operation of the pen thus described is as follows:

In filling, the cap 13 is removed from the pen end of the barrel, and is placed upon 55 the opposite end after first loosening the screw 24 by backing it off two or three turns. The clip rod 20 is lifted clear of the clip 16, swung around in the bail until it can be pushed through the opening 21 and screwed 60 in the plunger 22. The pen is then dipped into an ink container, and the rod is pushed in so as to force the plunger down through the length of the cap, thereby forcing air through the passage 23 and collapsing the 65 ink bag 12, while the pen remains immersed

in the ink. The cap 13 is then removed entirely from the barrel 1, and in a few seconds the sack 12 will be filled by atmospheric pressure and capillary attraction, assisted by the resilience of the bag. The rod 70 20 is then unscrewed from the plunger 22 after pulling the plunger up to the inner end of the cap, and the bail 18 is re-turned until the rod again engages the spring holder 16, when it will be in position as 75 shown in Fig. 1 to serve as a holding clip adapted to engage the flap of a pocket.

When using the filler with a pen barrel having no ink sack, the plunger is first pushed all the way down in the cap, the cap 80 is placed on the upper end of the barrel, the pen end is inserted in a vessel of ink, and the plunger is withdrawn, thereby creating a partial vacuum in the barrel, which causes the ink to rise therein by atmospheric pressure. The cap is then removed and the screw 85 24 is turned down to close the opening 23, when the pen is ready for use.

The form of clip shown in Figs. 3 and 4 is somewhat different from that in Fig. 2, 90 but is based on the same principle of using the clip rod 20 for a filler. The band 29 is solid, and carries two sleeves 31 and 32 into which the rod slides, a guide ring 33, and a small spring latch 34, adapted to engage a 95 notch 30 in the rod when the latter is in position (see Fig. 4). When in use with the filler, the rod functions the same as before described.

It will be observed that in regard to the 100 auxiliary reservoir 4 of Fig. 1, I have achieved a very desirable object, because when the pen is set vertically in the pocket, the ink will drain out of the tube and tend to produce a partial vacuum in the chamber or receptacle for overflow ink. The slightest expansion due to heat will therefore be relieved without pressure on the ink in the barrel, and flooding thereby becomes impossible.

I wish it distinctly understood that many changes and modifications in matters of detail are contemplated by me as a part of this invention, and can be made without departing from the scope thereof, as defined in the 115 appended claims.

Having thus described my invention what I claim and desire to secure by Letters Patent is:

1. A fountain pen with a barrel, a feed 120 plug and pen, a cap fitted with a plunger, and a rod or clip attached to said cap and adapted to be engaged with said plunger for filling the barrel, said barrel having an opening as 23 whereby the plunger may be effective to fill the barrel.

2. A fountain pen comprising a barrel, a pen, a cap fitting both ends of the barrel, a plunger or piston in the cap, a rod adapted to engage the plunger for pumping 130

ink into the barrel while the cap is in place on the upper end thereof, and means to secure said rod on the outside of the cap in position to form a clip when the cap is on 5 the pen end of the barrel, said barrel having an opening as 23 whereby the plunger may be effective to fill the barrel.

3. A fountain pen comprising a barrel, a pen, a cap, a holding clip and a filler device 10 carried on the cap, and a rod forming part

of the clip adapted also to engage the filler device for forcing ink into the barrel.

4. A fountain pen comprising a barrel, a pen, and a combined cap and filler, said cap carrying actuating means for the filler ad- 15 justably mounted to act as a clip when the pen is closed and in disuse.

In testimony whereof I affix my signature.

BENJAMIN R. JOLLY.
